United States Patent

Des. 236,781

Patented Sept. 16, 1975

236,781

COMBINED BOOKSHELF AND STORAGE CABINET OR SIMILAR ARTICLE

Gary Cowley, 2331 Main, Vancouver,
British Columbia, Canada

Filed Oct. 2, 1973, Ser. No. 402,774

Term of patent 14 years

Int. Cl. D6—04

U.S. Cl. D6—165

FIG. 1.

FIG. 2.

FIG. 3.

FIG. 4.

FIG. 1 is a front elevational view of a combined bookshelf and storage cabinet or similar article showing my new design;

FIG. 2 is a top plan view;

FIG. 3 is a left side elevational view; and

FIG. 4 is a right side elevational view.

The rear of the combined bookshelf and cabinet is plain and unornamented.

I claim:

The ornamental design for a combined bookshelf and storage cabinet or similar article, substantially as shown and described.
